UNITED STATES PATENT OFFICE.

BERNARD W. LYNCH, OF WILMETTE, ILLINOIS.

CHECK-BOOK.

1,329,002.

Specification of Letters Patent. Patented Jan. 27, 1920.

Application filed February 25, 1918. Serial No. 218,945.

To all whom it may concern:

Be it known that I, BERNARD W. LYNCH, a citizen of the United States, residing at Wilmette, in the county of Cook and State 5 of Illinois, have invented certain new and useful Improvements in Check-Books, of which the following is a specification.

The present invention has to do with improvements in banking books and the like, 10 and relates both to means for carrying the checks and for keeping account of the deposits and withdrawals to and from the checking account.

In my Letters Patent of the United States, 15 No. 1,099,708, issued to me June 9, 1914, for improvements in folding pad-holding cover, I have disclosed an arrangement in which a pad of checks may be detachably connected to a folding cover, and in which a pad of 20 leaves relating to bank deposits and withdrawals may also be detachably connected to the folding cover.

In the disclosure of that patent, the checks are mounted in book form, and as such are 25 detachably connected to the folding cover as a unit. This makes it necessary to bind or secure the checks together into pad form in the first place, and to this extent the arrangement disclosed in that patent is objectionable.

One of the objects of the present invention is to provide a folding cover, into which the individual checks may be detachably or removably seated and from which they may 35 be withdrawn one at a time, the checks being held in place as a group or unit, but nevertheless being quite independent or disconnected from each other.

Another feature of the present invention 40 has to do with the form and arrangement of the book or group of leaves, whereby the condition of the bank balance is followed and kept track of. In this connection, an object is to provide a book wherein the facing leaves, when the book is opened at any point, will be devoted to bank deposits and bank withdrawals respectively, so that the possibility of confusing deposits and withdrawals will be to that extent eliminated.

50 Other objects and uses of the invention will appear from a detailed description of the same, which consists in the features of construction and combinations of parts hereinafter described and claimed.

In the drawings:

Figure 1 shows a perspective view of one embodiment of the features of my invention, being that in which the bank book is detachably connected to the folder, the individual checks being seated in the check portion of the cover;

Fig. 2 is an end view of a modified arrangement in which the bank book is secured to one leaf of the folder by being pasted in place;

Fig. 3 is an end view of another modified arrangement similar to that shown in Fig. 2, with the exception, however, that the cover or folder is provided with an additional flap or leaf intended to overlie the check leaf 70 when the folder is completely folded up;

Fig. 4 is a cross section through the arrangement shown in Fig. 1;

Fig. 5 is an end view corresponding to Figs. 1 and 4, with the pad folded up;

Fig. 6 is a front face view of one of the leaves of the bank book; and

Fig. 7 is a view of the reverse side of the leaf shown in Fig. 6.

I will first describe the arrangement shown in Figs. 1, 4 and 5, and will afterward describe the modifications.

The folder shown in Figs. 1, 4 and 5 comprises the check leaf 10 and the book leaf 11, which are made of any suitable material, 85 such as leather, or imitation leather, cardboard faced with cloth, or any other material desirable for the purpose. The leaves can be folded with respect to each other along the line 12.

The bank book comprises a series of leaves 13, bound together in their folding portions 14 and provided with a flap 15, by which they are connected or attached to a leaf 11 of the folder. In the particular construction of Figs. 1, 4 and 5, this connection is effected by way of tongues 16 struck from the flap 15 and passed through slits cut in one or more layers of the leaf 11, so that the book can be connected to the leaf 11 by 100 slipping the tongues through the slits in a manner which will be well understood from an examination of the several figures.

In the construction of the aforementioned Letters Patent, No. 1,099,708, the checks are 105 shown as being bound together into book form, and attached to the leaf 10 in a manner similar to the attachment of the bank

book itself. In the arrangement herein disclosed, I provide a series of corner plates 17, 18 and 19, beneath which the corners of the individual checks 20 may be inserted 5 so as to hold said checks in place. Ordinarily, I prefer to provide three such corner plates, leaving the fourth corner 21 of the checks exposed, so that the checks can be more readily manipulated, both for insertion 10 and removal. In fact, I find it a great advantage in the practical use and operation of this device to leave one of the corners thus exposed, instead of covering over all four of the corners.

15 It will be observed that with this arrangement not only can the individual checks be readily manipulated both for insertion and removal, but also that there is no necessity for binding together the individual checks 20 into book form, and as a matter of fact it would be detrimental or undesirable to bind them together, because it would to that extent increase the difficulty of individually removing the checks.

25 It will be further observed that in each of the several forms illustrated in the drawings, the checks are held in place by the construction or arrangement just explained. However, in the modified construction shown 30 in Fig. 2, the bank book has its leaf 22 pasted or otherwise secured to the leaf 11 of the folder, instead of making use of the tongues 16 previously explained. The arrangement of Fig. 2 presents the advantage 35 that there is no danger of the bank book becoming detached or separated from the folder.

The arrangement shown in Fig. 3 is similar to that just described, with the additional feature that it is provided with a supplementary flap 23 which will overlie the check leaf 10 when the folder is completely folded up, the flap 23 being provided with a tongue 24 adapted to seat under a strap 45 25 on the leaf 10.

The bank book comprises the individual leaves 13, each of which is printed on its front face with rulings 26 for deposits and on its back face with inverted rulings 50 27, for withdrawals, so that no matter at what point the book is opened the deposit rulings 26 will appear on one page and the withdrawal or check rulings 27 will appear on the opposite page, both being simultaneously visible to the user.

The deposit rulings 26 include a column 28 for dates; a column 29 for amounts of deposit; and a column 30 for notations of payer or depositor, etc.

60 The check rulings 27 include a column 31

for dates; a column 32 for check numbers; a column 33 for amounts; and a column 34 for payees, and details of checks drawn.

At the bottom of the deposits column 29 is a footing 35 for total deposits; a footing 36 65 for total checks; and a footing 37 for balance forward.

At the bottom of the checks column 33 is a footing 38 for total checks drawn, which is the same item as is specifically entered in 70 the footing 36.

It is to be observed that in those cases in which the check or bank book is detachably connected to the folder it may be used separately from the checks themselves, although 75 ordinarily the two will be used in the combination which is secured by the use of the folder.

While I have herein shown and described only certain embodiments of my invention, 80 still it will be understood that I do not limit myself to the said embodiments except as I may do so in the claims.

I claim:

1. In a check book or the like, the combination of a folding cover comprising a pair of leaves folding on a line of crease across the width of the cover, one of said leaves having corner plates in three of its corners for the accommodation of a bunch of disconnected checks, leaving the fourth corner of the checks free, a bank book comprising leaves secured together on a common line of folding and attached along said line of folding to one of the leaves of the folding 95 cover, the pages of said leaves alternately displaying rulings for deposits and rulings for checks drawn, all of said rulings facing one edge of the holder when the pages are displayed, substantially as described. 100

2. In a check book or the like, the combination of a folding cover comprising a pair of leaves folding together on a line of folding extending across the width of the cover, a bank book comprising a series of leaves 105 joined together in their central portions on a line of folding, a connection between said line of folding and the upper portion of the upper leaf of the folder, the pages of said leaves being ruled alternately to display 110 rulings for deposits and rulings for checks drawn on consecutive pages, all of said rulings facing one edge of the folder, and corner plates on three of the corners of the lower leaf of the folder for the accommodation 115 of a bunch of disconnected checks leaving the fourth corner free, substantially as described.

BERNARD W. LYNCH.
